United States Patent Office

Des. 189,455
Patented Dec. 20, 1960

189,455

DOLL

Pascal M. Kamar, 3006 Crenshaw Blvd.,
Los Angeles, Calif.

Filed Jan. 8, 1960, Ser. No. 58,965

Term of patent 14 years

(Cl. D34—4)

FIG. 5.

FIG. 6.

FIG. 7.

FIG. 8.

Fig. 1 is a front elevational view of a doll embodying my invention.

Fig. 2 is a side elevational view thereof, both sides being identical.

Fig. 3 is a rear elevational view thereof.

Fig. 4 is a perspective view thereof, with its flexible legs bent.

Figs. 5 to 8 are views corresponding, respectively, to Figs. 1 to 4 but showing a different embodiment of the same design.

I claim:

The ornamental design for a doll, as shown and described.
